UNITED STATES PATENT OFFICE.

BERNHARD SCHAEFER, JR., OF CINCINNATI, OHIO.

DESIGN FOR A LIGHTING FIXTURE OR SIMILAR ARTICLE.

Application filed May 22, 1925. Serial No. 13,538. Term of patent 7 years.

To all whom it may concern:

Be it known that I, BERNHARD SCHAEFER, Jr., a citizen of the United States of America, residing at Cincinnati, in the county of Hamilton and State of Ohio, have invented a new, original, and ornamental Design for Lighting Fixtures or Similar Articles, of which the following is a specification, reference being had to the accompanying drawing, forming a part thereof.

In said drawing, the view is a front elevation of a wall-bracket lighting-fixture showing my new and ornamental design.

I claim:—

The ornamental design for a lighting fixture or similar article, as shown.

BERNHARD SCHAEFER, JR.
